(57) **CLAIM**

The ornamental design for a hair dryer, as shown and described.

DESCRIPTION

FIG. 1 is a front view of a hair dryer, illustrating our new design;

FIG. 2 is an enlarged top view thereof;

FIG. 3 is an enlarged bottom view thereof;

FIG. 4 is a rear view thereof;

FIG. 5 is a right side view thereof;

FIG. 6 is a perspective view thereof; and,

FIG. 7 is a left side view thereof.

The broken lines illustrate portions of the hair dryer that form no part of the claimed design.

1 Claim, 7 Drawing Sheets
